INSULATION MEANS FOR ELECTRICAL APPARATUS

James M. England, Lebanon, Mo., assignor of one-third to David E. Owen, St. Louis, Mo.

Application May 26, 1944, Serial No. 537,511

Claims. (Cl. 174—83)

1

My invention relates to electrical apparatus and more particularly to improved insulation means for the conductor slots of an electrical apparatus such as a motor or generator.

One of the objects of my invention is to provide specially constructed insulation strips for mounting in conductor slots prior to the placing of the conductors therein.

Another object of my invention is to provide slot insulation means which can be readily installed in the slots and automatically held therein without the necessity of special holding means.

Yet another object of my invention is to provide individual sheets of insulation material for mounting in conductor slots and thus eliminate the wastage of insulation material present in the use of a continuous strip passing into and out of successive slots.

Still another object of my invention is to provide improved insulation means for the conductor slots of an electrical apparatus which, when installed, will not decrease the width of the slot opening through which the conductors must be passed during winding.

Other objects of my invention will become apparent from the following description taken in connection with the accompanying drawings in which Figure 1 is an end view of a rotor showing my improved paper insulation sheet positioned in one of the conductor slots; Figure 2 is a top view of the rotor, showing it as prepared for winding; Figure 3 is a sectional view taken on the line 3—3 of Figure 1, said view additionally showing the end insulation plate in position; Figure 4 is a perspective view of the insulation sheet formed for assembly in a slot; Figure 5 is a plan view of the sheet as cut from a strip of paper; Figure 6 is a view showing the manner in which the insulation sheet can be shortened for use in slots of lesser length; and Figures 7 and 8 are views showing a modified construction.

Referring to the drawings in detail and first to Figures 1 to 5, my invention is shown as embodied in insulation means for the conductor receiving slots of a rotor, but it is to be understood that it can be employed in any conductor receiving slot whether in a rotor or stator or other member. Figure 5 shows the insulation means as it can be made for assembly. In this form it comprises a single sheet 1 of insulation material such as special paper of fairly heavy body similar to light cardboard (shown exaggerated in thickness in the drawing). This sheet is of rectangular shape and provided at its end with notches 2 which may be

2

instead of being notched, the ends may be merely slit longitudinally. The notches are arranged so that tabs 4 are formed in each end of the main body 3 of the sheet, said tabs lying on opposite sides of the longitudinal axis of said sheet. Cross scores 5 are provided between the tabs and the main body of the sheet, said scores being slightly spaced inwardly of the inner ends of the notches.

This insulation sheet is adapted to be placed in each conductor receiving slot 6 of the rotor 7 shown in Figures 1, 2, and 3, said rotor being of well-known construction and carried on the rotor shaft 8. The slots 6 have reduced openings 9 at the surface of the rotor and resulting from the under-cutting of the portions 10 of the rotor remaining between the slots.

To mount the insulation sheet in the rotor slot and thereby provide insulation between the conductors to be placed therein and the rotor, both ends of the sheet are bent in the same direction with respect to the body 3 of the sheet, the bending taking place along scores 5. The body of the sheet is next turned upon itself about its longitudinal axis to provide a U-shaped "trough-like" form. The shape of the sheet after the bending of the ends and turning of the body portion is shown in Figure 4. The sheet is now ready for insertion in the slot and is positioned therein by pushing it through the reduced opening 9 in the rotor surface with the curved portion entering the slot first. As soon as it is completely received in the slot, the sides will spring outwardly and the sheet will be held in position by the edges engaging the under-cut surfaces of the rotor portions 10. In this position the sheet covers both the side walls and bottom walls of the slots.

The length of the body of the sheet between the scores corresponds to the length of the slot. Thus tabs 4 on the sheet, which extend away from the body of the sheet due to the folding at the scores, are now in a position where they overlie the end surfaces of the rotor adjacent the open ends of the slot. By having the scores at the places indicated, that is, slightly spaced inwardly from the inner end of the notch, a small turned over portion indicated at 11 will result which will overlie the corner or edge at the ends of the bottom of the slot, thereby insulating this corner.

Prior to being wound, rotors are provided with insulation end plates or members. These members are of fairly heavy fiber board and conform in shape to the cross-section of the rotor, that is, they have slots the same size and shape as the rotor slots and teeth of the same size and shape as the rotor portions 10. Such end plates 12 are

shown in Figures 2 and 3. They are held against the end surfaces of the rotors by temporary collars 13 and 14 (Figure 2) which may also be made of fairly heavy fiber paper and secured to the rotor shaft by any suitable means. When my improved insulation sheet is used for the rotor slots, these end plates 12 are employed to clamp tabs 4 and the slightly turned over portions 11 against the end surface of the rotor and thereby firmly hold the sheet in the slot and positively prevent shifting either longitudinally, laterally, or radially. Thus it is seen that no gluing or other special means is necessary to hold the sheet in the slot. Also, the entire slot is properly insulated including the corners at the juncture of the walls of the slot and the end surfaces of the rotor.

From the foregoing it is seen that my improved insulation sheet is very simple in construction and easily assembled. When assembled it is firmly held in position by the usual end insulation plates. The sheet provides full insulation for the slot. Also, the openings of the slot at the rotor surface are not decreased in width by the insulation sheet as is the case when a sheet of paper from a roll is passed in and out of successive slots. My sheets also do not result in any waste of insulation material as is the case when a strip of insulation paper goes from one slot to another.

How the insulation sheet can be used for slots having a shorter length than that for which the sheet was cut is shown in Figure 6. The body 3 of the sheet is cut in two to form two sheets 15 and 16 and the cut ends are overlapped. By means of this cutting and overlapping, a rewinding shop need only buy one length of insulation sheet for several lengths of rotor slots, this length being the one for the slots of the longest rotor of the several rotors. Fewer different sheet lengths will be required to be made or kept in stock.

The modified insulation means shown in Figures 7 and 8 also comprise a sheet 1' with the cross score 5' adjacent the end shown. The end of the sheet has a curved cut 17 the ends of which are spaced slightly from the cross score as shown. There is also provided an axial cut 18 extending from the end edge to the curved cut. These cuts form the tabs 4' and a small central tab 19. When the sheet is bent and placed in the rotor slot, as shown in Figure 8, the tabs 4' will overlie the end surface of the rotor laterally of the slot and the tab 19 will cover the corner or edge at the end of the bottom of the slot. The arrangement insures that the entire end corner or edge of the slot will be insulated. The end plates when positioned on the rotor will cover all the tabs and hold the insulation sheet from shifting.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. An insulation means for placing in electrical conductor receiving slots comprising a sheet of insulation material rectangular in shape, notched at one end to provide holding tabs on opposite sides of its longitudinal axis, and cross scored slightly inwardly from the inner end of the notch so that when the sheet is turned upon itself about its longitudinal axis for reception in the slot the sheet can also be bent at the cross score to thus position the holding tabs in later-

ally outwardly extending direction and provide a turned over portion to overlie the end edge of the bottom of the slot.

2. In electrical apparatus, the combination with 5 a member having conductor receiving slots, of insulation means for a slot comprising a sheet of insulating material of such width that when turned upon itself about its longitudinal axis it will cover the bottom and side walls of the slot 10 and have its side edges positioned inwardly of the slot opening, said sheet being provided with tab means at one end arranged to be positioned to extend laterally outwardly, and means for holding said tab means against the end surface of the 15 member adjacent the slot.

3. In electrical apparatus, the combination with a member having conductor receiving slots, of insulation means for a slot comprising a sheet of insulating material of such width that when turned upon itself about its longitudinal axis it will cover the bottom and side walls of the slot 20 and have its side edges positioned inwardly of the slot opening, said sheet being of greater length than the slot in order to provide end portions 25 which can be positioned to extend laterally outwardly for cooperation with the end surfaces of the member adjacent the slot, and end members for clamping the end portions of the sheet against the end surfaces of the member.

4. An insulation means for conductor receiving slots of an electrical apparatus, said means comprising two sheets of insulation material each adapted to be turned upon itself to provide a member of U-shaped cross section and of such length 30 that when placed in the slot there will be overlapping relation of the inner ends, each of said sheets being provided at its unlapped end with holding tab means extending laterally outwardly with respect to the sheet when received in the slot.

40 5. In electrical apparatus, the combination with a member having conductor receiving slots, of insulation means for a slot comprising two sheets of insulating material positioned in the slots so that one end of one sheet is in overlapping relation to one of the other sheets, each of said sheets being of such width that when turned upon itself about its longitudinal axis it will cover part of the bottom and side walls of the slot and have its side edges positioned inwardly of the slot surface 45 opening, each of said sheets being provided at its unlapped end with tab means positioned outside the slot, and end members associated with the slotted member for clamping the tab means against the end surfaces of the slotted member.

55 6. An insulation sheet for conductor receiving slots comprising a body portion of rectangular shape having a cross score spaced from one end and provided with cuts extending inwardly from the end edge but short of the score to thereby provide portions outwardly of the score for covering the end edges of the slot when the sheet is turned upon itself about a longitudinal axis for reception in the slot and bent at the score so that the portion between the end edge and the score extends laterally outwardly.

7. An insulation sheet for conductor receiving slots comprising a body portion of rectangular shape having a cross score spaced from one end edge and provided with cuts extending inwardly 70 from the end edge toward the cross score for forming a central narrow tab and tabs on each side thereof, said cuts being of such length that no part of the sheet closely adjacent the score will be cut to thereby provide a covering for the end edge of the slot when the sheet is placed in

the slot after turning the sheet on itself about a longitudinal axis and folding it at the cross score so that all the portions between the score and the end edge extend laterally outwardly, said sheet being of such width that when turned a 5 U-shaped channel will result which is of less height than the depth of the slot.
